UNITED STATES PATENT OFFICE.

CHARLES BALTRUWEIT, OF NEW YORK, N. Y.

COMBINED WAGON, SLEIGH, AND BOAT.

SPECIFICATION forming part of Letters Patent No. 609,649, dated August 23, 1898.

Application filed April 8, 1898. Serial No. 676,884. (No model.)

To all whom it may concern.

Be it known that I, CHARLES BALTRUWEIT, of the city of New York, borough of Manhattan, in the county and State of New York, have invented a new and Improved Combined Wagon, Sleigh, and Boat, of which the following is a full, clear, and exact description.

The object of the invention is to provide a new and improved vehicle, combining a wagon, a sleigh, and a boat, and arranged to permit of conveniently and rapidly changing the vehicle from one form to the other, according to the condition of the route to be traveled, the vehicle being more especially designed for the use of hunters, fishermen, miners, and for other purposes.

The invention consists of novel features and parts and combinations of the same, as will be described hereinafter and then pointed out in the claims.

Reference is to be had to the accompanying drawings, forming a part of this specification, in which similar characters of reference indicate corresponding parts in all the figures.

Figure 1 is a side elevation of the improvement arranged as a wagon. Fig. 2 is an enlarged transverse section of the same on the line 2 2 of Fig. 1. Fig. 3 is a similar view of the same on the line 3 3 of Fig. 1. Fig. 4 is a longitudinal sectional elevation of the improvement arranged as a boat. Fig. 5 is a plan view of the same. Fig. 6 is an enlarged plan view of the sectional propeller-wheel. Fig. 7 is a transverse view of the shaft for the propeller-wheel, and Fig. 8 is a face view of the inner end of one of the propeller-wheel wings.

The improved vehicle is provided with a front axle A, carrying the front wheels B, and a rear axle A', carrying the rear wheels B'. A tongue or pole C is connected with the front axle A for drawing the vehicle over the ground, say in the form of a wagon, as illustrated in Figs. 2 and 3. On the front axle A is held a bolster D by means of a removable king-bolt E, and the ends of said bolster are fastened by bolts D' to the runners F of the sleigh, said runners extending to the rear of the axle A' to be fastened thereto by bolts F'. From the runners F of the sleigh extend upwardly the front and rear posts F² F³, of

which the front posts are connected with each other by a cross-beam F⁴, and the rear posts F³ are connected with each other by a cross-beam F⁵. On the cross-beams F⁴ F⁵ is adapted to rest the vehicle-body in the form of a boat G, preferably having a flat bottom and formed with a bow-section G', a middle section G², and a stern-section G³, the sections being fastened together at their adjacent ends by suitable bolts G⁴ and each section in the form of a box, as is plainly indicated in Fig. 5.

The forward or bow section G' of the boat is fastened in place by set-screws F⁶, carried in the posts F², and similar screws F⁶, screwing in the posts F³, engage the outside of the stern-section G³ to prevent the boat from slipping in a longitudinal direction on the cross-beams F⁴ and F⁵. The bow-section G' is also adapted to rest with its forward end on a cross-beam F⁷, connecting the upwardly-turned ends of the runners F with each other. By the arrangement described it is evident that by loosening the set-screws F⁶ the boat G may be readily lifted off its support, to be then launched in the water for traveling on a waterway to the desired place, the runners F and the front and rear axles being supported within the boat.

When it is desired to use the vehicle as a sleigh, the bolster D is removed from the runners F by removing the bolts D', and the front axle with its wheels B and tongue C can then be stored in the boat G, which forms the bed for the sleigh. The rear axle, with its wheels B', is removed from the runners F by loosening the bolts F', and the rear axle is also stored in the boat. The vehicle is now in the form of a sleigh and can be readily pushed or pulled over frozen ground, snow, or ice.

In order to propel the boat in a river or other waterway, I prefer to employ a propeller-wheel H, having a shaft H'; provided with journals H², mounted to turn in suitable bearings in a frame I, bolted or otherwise removably secured to the rear end of the stern-section G³, as is plainly illustrated in Figs. 4 and 5. The shaft H' is provided with apertures H³ H⁴, standing at a right angle to one another, as is plainly indicated in Fig. 7, each aperture being adapted to receive from op-

posite sides the reduced shoulders H^6 of the propeller-wings H^5 , so that the shoulder H^6 of one wing extends upon the other wing, and both are then fastened by a bolt H^7 , as will be readily seen in Figs. 5 and 6. By removing the bolt H^7 the wings can be readily drawn out of the shaft to permit of storing the propeller-wheel in a comparatively small space in the boat when it is desired to propel the boat by the wheels.

On one end of the shaft H' is secured a sprocket - wheel J , over which passes a sprocket-chain J' , also passing over a sprocket-wheel J^2 , secured on a shaft J^3 , journaled in the upper portion of the frame A. A second sprocket-wheel J^4 (see Fig. 5) is secured on the said shaft J^3 , and over this sprocket-wheel passes a sprocket-chain J^5 , also passing over a sprocket-wheel J^6 , attached to a shaft K, journaled in suitable bearings I', secured to the stern - section G^3 of the boat. On the shaft K is secured a crank-arm K', adapted to be turned by the operator in the stern-section of the boat, so that the rotary motion thus given to the shaft K is transmitted by the sprocket-wheels J^6 , J^4 , J^2 , and J and the sprocket-chains J^5 , J' to the propeller-wheel shaft H' , so that the propeller-wheel is actuated to propel the boat forward or backward, according to the direction in which the crank-arm K' is turned.

The boat G can be readily steered by the use of a rudder in the hands of one of the occupants of the boat, said rudder being preferably the detached tongue or pole C, widened at one end.

In case the boat is to travel in comparatively deep water centerboards L are employed, inserted in centerboard-chambers G^5 , formed longitudinally in the bow and stern sections G^1 and G^3 , as is plainly shown in Figs. 4 and 5. The upper ends of the centerboards L are provided with flanges L', which rest on the top of the chambers G^5 , the lower ends of the centerboards extending a suitable distance below the bottom of the boat. It is understood that the chambers G^5 are in longitudinal alinement with each other at the center line of the boat. When the centerboards are not used, the upper ends of the chambers

G^5 are closed by suitable hinged covers G^6 . (Indicated in Fig. 3.) The centerboards when not used as such may be employed for covering over the boat.

Now it will be seen that by the arrangement described the vehicle can be readily transformed into a wagon, sleigh, or boat, so as to enable a person to readily travel over the ground or over snow and ice or over a water-way and at the same time be able to carry complete luggage, &c.

Having thus fully described my invention, I claim as new and desire to secure by Letters Patent—

1. A vehicle, comprising a wagon, a sleigh and a boat, the latter being arranged to form the body for the sleigh and the wagon, substantially as shown and described.

2. A vehicle, comprising a wagon, a sleigh and a boat, the latter being arranged to form the body for the sleigh or the wagon, said sleigh having its runners forming the connection between the front and rear axles of the wagon, substantially as shown and described.

3. A vehicle, comprising a front and a rear axle, a bolster connected by a king-bolt with the front axle, sleigh-runners secured to the said bolster and rear axle, and a boat removably carried by said runners, substantially as shown and described.

4. A vehicle, comprising a front and a rear axle, a bolster connected by a king-bolt with the front axle, sleigh-runners secured to the said bolster and rear axle, a boat removably carried by said runners, and a pair of posts on the said runners, the posts of each pair being connected with each other by a cross-beam to form supports for the said boat, substantially as shown and described.

5. A vehicle provided with a sectional boat, a propeller-wheel made in knockdown sections, a frame adapted to be secured to the rear end of the boat and in which said wheel is journaled, and a hand - actuated driving mechanism for the said wheel, substantially as shown and described.

CHARLES BALTRUWEIT.
